Specification of Letters Patent.

Patented Nov. 18, 1919.

Application filed February 21, 1919. Serial No. 278,499.

To all whom it may concern:

Be it known that I, WILLIARD H. BRISCOE, a citizen of the United States, residing at Mission, county of Hidalgo, Texas, have 5 invented a certain new and useful Improvement in Heaters, of which the following is a full, clear, and exact description, such as will enable others skilled in the art to which it appertains to make and use the same.

10 My invention relates to heaters and has special reference to heaters designed for use in orchards for raising the temperature of the atmosphere at times when frosts or freezing temperature is threatened.

15 There have been many heaters of various designs produced for the purpose of heating orchards but most of these are only partially successful. The object of my invention is to produce a heater which is simple 20 in structure and cheap to manufacture and which will at the same time be efficient in raising the temperature of the atmosphere in the vicinity.

Another object is to produce a device of 25 the character described which will be capable of burning oil or other similar hydro-carbon and which will allow a plentiful supply of air in such a manner as to cause approximately complete combustion.

30 Referring to the drawings forming a part of this specification and in which like characters of reference are applied to like parts throughout the views, Figure 1 is a side view in elevation showing the exterior 35 construction of my improved heater. Fig. 2 is a longitudinal section through my heater, showing the interior construction thereof. Fig. 3 is a top plan view of the same.

40 My heater is specially adapted for burning crude oil or petroleum and is formed with a lower container 1, preferably cylindrical in shape, said container having an upper frusto-conical inclined portion 2, terminating in a cylindrical nipple 2', which may be crimped or fluted as shown in Fig. 3. This nipple connects the container 1, with an elongated outlet pipe 3, designed to carry off the products of combustion. This outlet 45 pipe or smoke stack 3, is detachably fitted over the nipple 2' and may be used or not as desired. At one side of the container 1, and toward the upper part thereof is a laterally extending spout or hearth 4, having an 50 upper approximately horizontal opening 5,

provided with a lid 6, adapted to close or regulate the size of the opening 5 and thereby control the draft when the heater is burning. This lid 6 is hinged at its inner end 7 and may be regulated as to the height to 60 which it is raised by means of an outer supporting member 8, pivoted, to the outer end of the lid at 9, and provided with notches 10 for contact with the outer end of the hearth 4 to adjust the amount of draft allowed. 65

The outlet pipe 3 is provided with a hood or cap 11, pivoted at 12 to one side of the said outlet pipe, so that it may be used to close the said pipe when desired. 70

In this type of heater, no wick or other device for feeding the fluid is necessary. The oil is poured into the heater until the same is filled, so that the level of the oil will stand nearly to the height of the opening 5. When it is desired to start the burner, the cap 11 is thrown back from the outlet pipe and the draft regulating lid 6 is lifted. A torch is then applied to the opening 5 so as to ignite the crude oil therein. 80 The speedy ignition of the crude oil may be facilitated by the use of a small quantity of gasolene or other inflammable substance at the hearth, if desired. The draft will enter the opening 5 passing in over the surface of the fluid and thence up the outlet pipe 3 carrying with it the products of combustion resulting from the burning of the oil. 85

When the oil is ignited at the hearth only, the combustion is not complete and although the heater sends out a very effective heat, there also is produced at the upper end of the outlet pipe 3 a smudge or smoke which will settle over the orchard and will serve in a small degree to prevent 90 the rapid radiation of heat upwardly from the ground as would otherwise take place in the absence of the blanket of smoke. If, however, the torch is applied to the top of the smoke stack 3 after the fire has been 100 burning a few minutes, combustion will also take place at the upper end of the pipe, and the products of the incomplete combustion at the surface of the oil, will be ignited and the smudge or smoke will practically 105 disappear, producing, however, an intense heat. The height of the lid 6 is usually adjusted to allow sufficient air to be fed into the heater, in order that the combustion of the fluid will be as nearly complete as possible. 110

The burner may be used without the smoke stack, or outlet pipe 3, if desired, but it has been found that the heater is not quite so efficient when so used, due no doubt to the 5 fact that the draft is not quite so good, and also to the fact that the heating area is increased by means of the said outlet pipe. The combustion at the upper end of the stack distributes the heat at a somewhat 10 higher level and more efficiently distributes the same through the atmosphere in the neighborhood of the trees in the orchard. When used without the smoke stack a greater degree of heat is obtained by igniting 15 the oil at the hearth as before, and by then again igniting the gas at the outlet nipple 2', as is done when the smoke stack is used. It has been found that the outlet pipe 3 is more efficient when a certain length 20 of pipe is used. If the heater is used without the pipe, it has been found not quite so efficient as when the pipe is used, and further if the pipe is increased in length unduly, a decrease in efficiency is observed. A 25 section of pipe about 24 inches in length for a heater of the size used in orchard work is found to be about right.

It will be seen that this device is capable 30 of varying adjustment for different purposes and is very efficient in any of the ways in which it is used. When serving both as a heater and as a smudge pot, it acts to heat the atmosphere in the neighborhood of the trees and the blanket of smoke produced by 35 the incomplete combustion of the oil will serve to retain the heat in the vicinity of the trees so as to effectively prevent a further fall in temperature. When used as a heater alone the amount of oil used in burning is 40 no larger than when used both as a heater and a smudge pot, but the volume of heat is greatly increased. When it is desired to confine the heat toward the lowest part of the trees or when used on small fruit the 45 smoke stack may be dispensed with and the heat will be largely distributed close to the earth. When intended for use with large trees where the danger of frost threatens all the trees, the use of the smoke stack will 50 greatly increase the volume of heat and will distribute the same more efficiently for the full height of the trees.

In practice these burners are installed at 55 regular intervals throughout the orchard and when it is found that the temperature is approaching the danger point for the fruit, the workmen will pass through the orchard lighting these burners in the manner described and the heat from the said burners 60 will act to keep the temperature of the

orchard within the limit of safety for the fruit.

When it is desired to put out the fires in the burners the draft is entirely closed and the cap 11 is shut down on the outlet pipe 65 3. This will prevent the entrance of air and oxygen to the fire and the same will be soon extinguished.

It has been found that these burners are 70 remarkably economical and efficient and when properly used will entirely prevent freezing in the orchard under any ordinary frosty night conditions.

While I have illustrated my invention as 75 being cylindrical in shape, it is obvious that this shape is entirely immaterial and it could be of any ordinary shape and I do not wish to confine myself to any particular form of apparatus, except as is limited in the claims hereto. The device is especially 80 adapted for burning petroleum, but it is obvious that other fluids could be used and the device is not limited to the particular burning of oil.

Having thus described my invention what 85 I claim as new and desire to protect by Letters Patent is:

1. A portable burner for liquid fuel, comprising a fuel container, a lateral hearth thereon, said hearth extending from the upper to the lower ends of said container so as to conduct air to the bottom thereof when required, a cover for said container, and an outlet pipe on said cover, said cover and outlet pipe being imperforate and the interior 95 of the container unobstructed, whereby the fuel in said burner is adapted to burn both at the hearth and at the upper end of said outlet pipe.

2. An orchard burner for liquid fuel comprising a container having its interior clear and unobstructed, an imperforate upwardly tapering cover thereon, an imperforate outlet pipe on said cover and a hearth on one side of said container adapted to deliver 100 air to the fuel at any level in said container and a damper on said hearth at the upper edge of said container.

3. A portable burner comprising a container for liquid fuel, an imperforate 110 tapered cover therefor, an imperforated outlet pipe on said cover, a lateral hearth on said container and extending from top to bottom thereof and an adjustable damper on the upper end of said hearth.

In testimony whereof I hereunto affix my signature this the 15th day of February 115 A. D. 1919.

WILLIARD H. BRISCOE.
